UNITED STATES PATENT OFFICE.

EDWARD C. DANDY AND WILLIAM TUGWELL, OF BALTIMORE, MARYLAND.

BRAIDER TENSION.

Application filed July 23, 1925. Serial No. 45,494.

The invention relates to a braider carrier improvement having particular reference to the tension-applying means. One of the difficulties universally encountered in this art at which numerous improvements have been directed, is that of applying the desired degree of tension to the yarn, and as the motion of the carrier changes the distance of the spool or tube from the point 10 of braiding in maintaining the tension without variation. The devices in use are more or less irregular and uncertain in their operation.

The present improvements comprise an 15 adjustable spring plate tension which provides a direct drag on the yarn which may be adjusted according to a spring balance to give the desired degree of tension, a brake which is so constructed as to compensate 20 for the change in radius, as the size and hence the radius of the ball or winding changes, and a weight and spring take-up which compensates and prevents slackening of the yarn when the motion of the carrier 25 causes the spool or tube to approach the point of braiding. The weight may also be utilized as a knock-off member to actuate any well-known or preferred type of stop motion. The plate spring tension and take-up are so constructed that they may be 30 threaded substantially with a single motion and without shifting the grip on the thread, no special implements or change of position or adjustment of the parts being necessary.

In the accompanying drawing we have 35 illustrated so much of a braider carrier as is regarded as necessary to a proper understanding of the various devices of the invention and the operation thereof.

In the drawings—

Figure 1 is an elevation of the carrier and tension members, etc., the table, i. e., the top, bottom and center plates being sectioned and fragmentarily shown, the elevation 45 being a view looking toward the centre of the spool from the side of the carrier arm.

Figure 2 is an elevation of the carrier and tension members, etc., and section of 50 the table taken from the right in Figure 1, both figures showing the yarn in threaded position.

Figure 3 is a fragmentary view corresponding to Figure 2, but showing the device in the process of threading.

Figure 4 is a horizontal section on the line 4, 5 of Figure 2, showing the tension drag or brake in connection with a spool from which but a small portion of the yarn has been removed, the tube being almost 60 full.

Figure 5 is a similar section showing the action of the brake or drag where from two-thirds to three-fourths of the yarn has been removed, the section being taken on the 65 same line.

Figure 6 is a section through the carrier arm and spring tension plate, the same being taken on the line 6, 6 of Fig. 1.

Figure 7 is a section on the line 7, 7 of 70 Figure 1 showing the take-up weight and spring.

Referring to the drawings by numerals, each of which is used to indicate the same or similar parts in the different figures, the 75 disclosure includes a fragmentary showing of a braider table 1, braider carriage 2 comprising the guides or followers 3 and 4 which co-operate with the table, and an upright arm 6 which carries the tension 80 members, yarn and guide, etc., to be described. The arm at its upper end is provided with an eye 7 through which the yarn is delivered to the point of braiding.

The tension members, as aforesaid, 85 comprise a brake 10, spring plate tension 11 and take-up 12. These three mechanisms contribute to the common result of applying to the yarn and maintaining a constant and predetermined or adjustable tension. 90 The yarn is led from the spool or tube 14 over the take-off guide 15 through an eye 16 in the upright arm 6, hence under the spring plate tension 11 to be described, which presses it into the vertical groove 17 95

in the arm, see Figure 6, the yarn itself being indicated by reference character 18. The yarn extends downward in the aforesaid groove 17 from the spring plate tension 11 around and beneath the bottom weight 19, 100 which is a feature of the take-up 12 to be more fully described, and then upward vertically from the lower edge of the bottom weight at the bottom of upright arm 6 through the eye 7 at the top of the arm 6, 105 from which point it is led to the point of braiding where it is embodied in the cord or rope being formed.

The operation of such braiding machines is well understood and need not be described. 110

The present invention relates to the different tension members already specified.

The brake 10 is in the form of a curved arm 20 which as shown is of a vertical width 5 equal to about one-third of the height of the bobbin, the curve being in a horizontal plane and the arm being pivoted at one end to a vertical hinge pin 21 mounted in suitable eyes 22 on the upright arm 6 of 10 the carrier, the brake arm 20 having corresponding eyes 23 through which the hinge pin 21 also passes, the pin 21 being further held in position by a cutter 24, Figures 1 and 2. This brake arm 20 is pressed against 15 the surface of the yarn or ball 25 on the spool or tube by a hinge spring 26 which is coiled about the pin 21 between the eyes 22 on the upright arm, one end of the spring bearing against the outside of the brake arm 20 25 and the other against the outside of the upright 6, the respective ends of the spring being indicated by reference characters 27.

It will be noted that one difficulty and 25 source of irregularity in the application of such a tension resides in the variation in the radius of the ball or winding of the spool or tube, which variation in radius as the ball is unwound causes a variation of 30 the angular position of the brake arm 20 about the pin 21 which changes and reduces the tension of the spring and the pressure of the arm as the spool or ball is unwound.

An important feature of the invention resides in the formation and construction of 35 the brake arm in such a manner as to compensate for this variation and to equalize the resulting pull on the yarn due to the friction of the brake arm as applied to the 40 surface of the ball. This is accomplished by so plotting the curve of the arm that the radius or distance from pin 21 of the point of contact of the arm with the surface of the ball decreases as the radius of 45 the ball decreases, so that as the spring tension decreases, the radius of the point of application of the spring pressure to the 50 yarn decreases, the ratio being such as to equalize the resulting friction and pull.

By reference to Figures 4 and 5 it will 55 be noted that the radius about pin 21 of the contact point 30 of the arm 20 with the ball or winding 25 in Figure 4, showing the ball of relatively large diameter, is considerably greater than the radius of contact point 31 about the same pin 21 in Figure 5 showing the ball of small diameter; in other words, the radius of the contact point varies with the change of radius of 60 the ball, decreasing the moment arm at which the drag is applied as the spring tension decreases and keeping the braking effect constant. The contact surface of the 65 brake lever arm 20 is as shown covered with leather or other fibrous material 33 which

gives a good friction contact with the surface of the yarn.

Another feature of the invention which is regarded as of importance is the spring plate tension 11. In the form of the invention shown the upright carrier arm 6 has a vertical groove 17 on its outer surface extending from the central eye 16 through which the thread is passed downward to a point near the bottom and just above the weight stop 34. In threading, as aforesaid, the yarn is passed from the take-off or tension guide 15 through the eye 16 downward along groove 17 around the bottom weight 19 and upward through the eye 7. The spring plate tension 11 overlies the outer surface of the arm 6, being secured to the arm at the top by screws 35 and 37 and bowed outward centrally at 36, the spring plate 11 extending downwardly from screw 35 along the upright arm 6 and bearing at its bottom end where it has a reverse curve 36 against the arm 6. When the carrier is threaded, the bottom end of the spring plate tension bears firmly against the yarn in the groove 17 just below the eye 16, the tension being regulated by the second screw 37 which is seated in the arm 6 and passed through the plate spring tension member 11 at a point in the curve 36 near the base thereof and spaced a little below the screw 35 which holds the spring plate tension in position. This screw 37 is known as an adjustment screw. By tightening it against the curved portion of the spring plate arm, the tension is varied at will and may be regulated or adjusted by means of a spring balance fastened to the thread to determine the tension applied thereto as the screw 37 is tightened or loosened.

An important feature of the spring plate tension 11 is the transverse eye slot 38 therein, which slot registers with the eye 16 in the upright carrier arm 6 and provides for convenient threading of the carrier and tension as particularly illustrated in Figure 3.

It will be easily understood that as the spring plate tension 11 necessarily overlies the eye 16, threading of the yarn through the eye would be exceedingly difficult in the absence of the eye slot 38 which makes it possible without interfering with the operation of the tension, to pass the end of the yarn from the inside outward directly through the eye 16 in threading. This slot 38 is conveniently widened toward the outer edge of the spring plate tension member 11, as shown, and the opening of the slot at the side of the plate 11 further provides for the threading in that it permits the yarn after being passed through the eye 16 and through the slot to be passed to the right in Figure 1 out of the slot and beneath the spring plate tension member 130

into the groove 17 along which it is passed downward under the bottom weight 19, being led between the weight and the arm 6 at the right where the weight is free as seen in Figure 1. Upon being sharply pulled, it passes between the bottom weight, and the upright arm 6 on which the bottom weight slides, as shown, particularly in Figure 7, threading being in this position 10 of the yarn completed except for the passing of the yarn upward along the groove 39, as shown in Figure 7, and threading it through the eye 7 at the top of the carrier arm from which eye it is led directly to the point of braiding. The position and arrangement of the slot 38 makes it possible to thread the carrier after the yarn has been passed through the eye 16 with practically a single motion, without implements 20 and without any elaborate mechanical steps or procedure.

Another important feature of the invention is the take-up 12 consisting of bottom weight 19 sliding in a vertical path on the 25 lower half of the upright carrier arm 6, the traverse of the bottom weight being limited at the bottom by the bottom weight stop 34 and at the top by the bottom weight spring stop 40. The bottom weight is provided with a slot 41 on its rear or inside surface, which slot fits loosely about the arm 6, which acts as a way for the bottom weight, the slot being partially closed about the upright arm 6 by lips 42. The bottom 30 weight as shown has at one side, preferably the left or the side opposite the opening of the slot 38, a vertical bore or hole 43 in which is seated a coil spring 44 which engages a shoulder 45 near the bottom of the hole. Below the shoulder the hole is of 35 reduced diameter as at 46, and the hole or bore 43 serves as a guide and bearing for the take-up pin 47, which is shouldered at 48 to engage the spring, providing a reduced portion 49 which extends downward through the coil of the spring and through the reduced opening 46 at the bottom where the pin is held by a cotter 50 or in any other suitable manner. The pin 47 is so placed 40 as to engage the spring stop 40 as the weight moves upward due to the tension of the yarn, and on further tension the bottom weight 19 is drawn up, compressing the spring and increasing the tension on 45 the yarn. The take-up 12 provides primarily during the operation of braiding for the maintenance of a continuous tension as the distance between the carriers and point of braiding varies slightly, tending in the absence of some such provision for a 50 constant tension to produce loops of projecting yarn or soft portions in the rope or cord being braided.

In the present device a marked degree 55 of tension sufficient to raise the weight 19

and compress the spring 44 to a considerable degree is exerted and applied to the yarn at all times during the braiding operation, such tension being necessary to unwind the yarn from the spool or ball, hence 70 a slight relaxation of the pull on the yarn is easily and quickly taken up by the spring 44 and the weight 19, the weight being correspondingly moved downward to take up the slack. 75

It should be noted that the feed of the present braider carrier is continuous as distinguished from the step by step feed of the carrier and tension device described in Hooper Patent No. 1,442,432, the weight 80 or block 12 being mainly for the purpose of taking up the slack which might result from the movement of the spindle in the braiding operation and having no tripping function as have the sliding blocks in the 85 previous braider carriers which in the upper portion of their travis trip a pawl which permits the spindle to rotate, letting off a supply of yarn for use until the loop is sufficiently shortened to again raise the 90 weight.

In the event of breakage of the yarn, the tension being relaxed, the weight 19 moves to bottom position in which it rests against the stop 34. In this position the movement 95 of the braider head brings it into contact with the knock-off lever 52 which may be connected to any preferred type of stop motion which throws off the belt or otherwise disconnects the power and stops the 100 machine until the break receives the attention of the operator and the machine is again started. Various types of stop mechanism suitable for this purpose being well known, no illustration of this feature other 105 than the knock-off lever is regarded as necessary.

The various mechanisms described operate simultaneously to apply, by their combined operation, a suitable uniform tension to the 110 yarn during braiding to produce a cord of the desired degree of hardness and closeness of braid, and of uniform appearance and texture.

The operation of these mechanisms has 115 been fully described in connection with the description of their structural features.

We have thus described specifically and in detail a braider tension, take-up and stop motion mechanism in accordance with our 120 invention in order that the nature and operation of the same may be fully understood; however, the specific terms herein are used descriptively rather than in their limiting sense, the scope of the invention being defined in the claims. 125

What we claim and desire to secure by Letters Patent is:

1. The combination in a braiding machine 130 of a braider carrier having a spindle carry-

- 4
- ing a supply of yarn, an upright arm having an intermediate eye and an eye at the top, a bottom weight sliding on the arm and a spring tending to depress the bottom weight, 5 a yarn take-off guide, a spring plate tension bearing on the outside of the arm below the intermediate eye and a spring pressed drag bearing on the surface of the yarn supply which is wound about the spindle, 10 the yarn being led from the spool about the guide outwardly through the eye in the centre of the upright arm downwardly along the upright arm beneath and about the bottom weight and upward through the eye 15 at the top of the arm and hence to the point of braiding, the spring tension bearing on the yarn just below the intermediate eye and pressing it against the upright arm.
2. The combination with a braider carrier, 20 the carrier having a spindle with a supply of yarn wound about the same, and an upright arm adjacent the spindle of a tension mechanism in the form of a brake engaging the peripheral surface of the yarn on the spindle, 25 the brake being in the form of a lever having a hinge connection with the upright arm, and a spring engaging the upright arm, and said lever pressing the latter against the surface of the yarn on the spindle, the brake 30 lever being formed on a curve so that its extreme outer end remote from the hinge bears on the yarn when the spindle is full and the ball is of the greatest diameter, the curve being so formed that the point of 35 contact shifts toward the hinge as the yarn is unwound, the curve being concave toward the spindle and the shifting of the point of contact tending to compensate for relaxation of the spring as the arm swings toward 40 the centre of the spindle.
3. The combination with a braider carrier of a tension consisting of a spring plate secured to the carrier at one end and bowed outwardly from the carrier and bearing at 45 the other end on the yarn after it has been led from the bobbin, pressing the same against the carrier and means for varying the tension on the spring by applying a varying degree of pressure to the latter at 50 a point where it is spaced away from the carrier.
4. The combination with a braider carrier having an upright arm with a transverse eye through which the yarn is threaded, of a spring plate tension bearing against the yarn adjacent the eye, the plate having a transverse open ended slot over the eye through 55 which the yarn may be passed in threading.
5. The combination with a braider carrier 60 having a transverse eye through which the yarn is passed, of a spring plate tension member pressing the yarn against the carrier adjacent the eye, the plate having an open ended slot through which the yarn may 65 be passed in threading and from which slot

it is led between the spring plate and the carrier to the point upon which the pressure is applied.

6. The combination with a braider carrier having a transverse eye through which the 70 yarn is passed, of a spring plate tension member pressing the yarn against the carrier adjacent the eye, the plate having a slot through which the yarn may be passed in threading and from which slot it is led between the spring plate and the carrier to the point upon which the pressure is applied, and a bottom weight mounted on a slide 75 below the eye, the weight fitting loosely on the slide and being free at one side so that the yarn may be passed between the weight and the slide and upwardly about the weight to the point of braiding.

7. The combination with a braider carrier having a transverse eye through which the 80 yarn is passed, of a spring plate tension member pressing the yarn against the carrier adjacent the eye, the plate having an open ended slot through which the yarn may be passed in threading and from which slot it is led between the spring plate and the carrier to the point upon which the pressure is applied, and a bottom weight mounted on a slide 85 below the eye, the weight fitting loosely on the slide and being free at one side so that the yarn may be passed between the weight and the slide and upwardly about the weight to the point of braiding, the braider weight having a spring which tends to press it downwardly to take up the 90 slack of the yarn.

8. The combination with a braider carrier having a spindle with a supply of yarn wound about the same, of a brake engaging the peripheral surface of the yarn on the 105 spindle, the brake comprising a swinging lever and a spring pressing the lever against the yarn, the lever being curved in the plane of oscillation whereby the radius of the point of contact about the centre of oscillation changes and decreases as the yarn is 110 unwound, compensating for the relaxation of the spring.

9. The combination with a braider carrier having a spindle, of a continuous feed and tension for the yarn comprising an upright arm with an intermediate eye through 115 which the yarn is passed from the spindle, a take-up member sliding on the upright arm which it but partially encloses, the take-up member fitting loosely on the upright arm and having an opening at the side through which the yarn may be swung laterally, so that the yarn being led downwardly from the eye may be passed laterally between the take-up member, and the upright arm, and thus looped under the take-up member, from which point it is led up to the top of the arm which is provided with an 120 eye through which the yarn is passed and 125

led from said eye to the point of braiding.

10. The combination with a braider carrier having a spindle for the yarn and an upright arm with an intermediate eye 5 through which the yarn is passed from the spindle, a take-up member sliding on the upright arm which it partially encloses, the take-up member fitting loosely on the upright arm and having an opening at the side 10 through which the yarn may be swung laterally, so that the yarn may be led downwardly from the eye and passed laterally between the take-up member and the upright arm, and thus looped under the take-up 15 member from which point it is led up to the top of the arm which is provided with an eye through which the yarn is passed and led from said eye to the point of braiding, and a spring plate tension on the arm bearing 20 on the yarn and pressing it against the upright arm at a point below the intermediate eye.

11. The combination with a braider carrier having a spindle for the yarn and an 25 upright arm with an intermediate eye through which the yarn is passed from the spindle, a take-up member sliding on the up-

right arm which it partially encloses, the take-up member fitting loosely on the upright arm, so that the yarn may be led 30 downwardly from the eye and passed between the take-up member and the upright arm, and thus looped under the take-up member from which point it is led up to the top of the arm which is provided with an 35 eye through which the yarn is passed and led from said eye to the point of braiding, and a spring plate tension on the arm bearing 40 on the yarn and pressing it against the upright arm at a point below the intermediate eye, the spring plate tension having a slot opening leading to the outside edge of the tension member, the slot registering with the intermediate eye for convenience in threading through the intermediate eye and 45 through the tension member whereby the yarn may be swung from the eye under the tension member and passed between the take-up and the upright arm.

Signd by us at Baltimore, Maryland, this 50
18th day of July, 1925.

EDWARD C. DANDY.
WILLIAM TUGWELL.
